SLIDE LOOP

George Henry Elwell, New Haven, Conn., assignor
to Eastern Tool and Manufacturing Company,
Bloomfield, N. J., a corporation

Application February 6, 1942, Serial No. 429,751

3 Claims. (Cl. 24—170)

This invention relates to slide loops and especially to slide loops of wire construction with a sheet-metal strap-secur ing means.

The objects of the invention are to provide a wire slide loop having upon its face no visible means of support upon a strap; to provide a wire slide loop having a wire formed entrance to the strap passage of narrow width and into which an intermediate length of a strap may be inserted laterally; to provide a wire slide loop in which a strap may be inserted lengthwise within the button loop from the front and then swung around to be inserted laterally within the strap passage; and to provide a wire slide loop with a sheet-metal strap-secur ing means co-operating with spaced wire arms in an intersecting plane thereto and thereby not interfering with the resilient action of the button loop arms.

Referring to the accompanying drawing, the Figure 1 is an upright face view of the device mounted upon a fabric strap; the Figure 2 is an upright rear view of the device, the sheet-metal member being in engaged position; the Figure 3 is an upright side view of the device in engagement with an inserted strap; the Figure 4 is a similar side view as in the previous figure but with the strap-engagement means in an open position, and a strap illustrated in dotted lines initially inserted vertically into the device; the Figure 5 is a top view of the device with the strap-engagement means in a closed position; the Figure 6 is a plan view of the wire formation, approximate as to measurements, before folding into parallel planes, and the Figure 7 is a face view of the wire portion of the device with the outline of a strap swung around into one side of the strap-passage.

With more particular reference to the accompanying drawing and especially to the Figure 6 with regard to the continuous wire formation of the device, before folding, an intermediate portion of the wire length, of about nine inches, provides the upper horizontal bar 1 having at both ends thereof the downwardly directed arms 2 and 2A which at the ends thereof the laterally outwardly directed companion strap loops 3 and 3A are spacedly formed within a horizontal plane, the wire formation continuing and downwardly directed from the companion loops 3 and 3A to provide the spaced parallel arms 4 and 4A relatively more close, one to the other, than the arms 2 and 2A, the arms 4 and 4A being directed at their ends into a horizontal plane and toward one another to provide the spacedly aligned bar portions 5 and 5A which at their inner ends are directed downwardly to provide the spaced par-

allel arms 6 and 6A terminating in the outwardly curved arms 7 and 7A of the button-receiving loop 8, the constricted throat portion 9 and the button-retaining loop 10. The wire structure thus formed is then folded backwardly along the dotted lines 11 and 12 to provide in spaced parallel and vertical planes the front and rear supports defining a strap passage X as illustrated by the Figures 3 and 4.

10 The sheet-metal member of the device, as illustrated by the Figures 2, 3, 4, and 5, has a hinged connection 20 with the horizontal wire bar 1 and integrally carries extending therefrom axially a strap-binding element 21 adapted to be swung into and out of the strap-passage X for engagement and disengagement with the spacedly parallel vertical bars or arms 6 and 6A, and a lift-guard 22 adapted to contact with a lower part of the wire structure to limit the swinging movement of the strap-binding element 21 into the strap-passage X.

15 In use, with the sheet-metal member of the device in the position illustrated by the Figure 4, the end of the strap S, upon which the slide loop is to be mounted, is inserted lengthwise from the front into the intercommunicating button-receiving and retaining loops 8 and 10, respectively, as also illustrated by the Figure 4 and the device thus passed along the length of the strap S until the device arrives at the place thereon where it is to be mounted and then the strap S is swung around within the intercommunicating loops 8 and 10 and into a transverse plane and one strap edge Sx laterally inserted within the left-hand 20 one of the companion strap-loops 3 and 3A as illustrated by the Figure 7 and the other strap edge Sx is then immediately inserted within the right-hand strap loop so that when the inserted strap S is straightened into alignment within the device, as illustrated by the Figure 1, the sheet-metal member 20 at the back of the device is swung into position within the strap-passage X, as illustrated by the Figure 3, to contact the strap-binding element 21 with the rear surface 25 of the less thick center Sxx of the inserted strap S which is thus wedged against the vertical parallel bars 6 and 6A, the element 21 having passed its centered position is there checked in its further movement by the lift-guard 22 in contact with the strap S positioned against the depending portion of the wire structure.

30 The advantages of this improved slide loop are that in manufacture it admits of a strap-passage of narrow width into which the strap fits tightly; that it provides for an inserted strap lying

throughout its inserted length in parallel relation to the plane of the slide loop; and that it permits the lateral insertion of a strap at the place of mounting.

I claim:

1. A wire slide loop comprising relatively spaced interfacing companion loop-ends flatly lying in a common horizontal plane with no relative connection in said plane; wire ends integrally depending vertically from the loop-ends to provide relatively spaced pairs of rear and front supports; a horizontal bar integrally connecting the pair of rear supports; a vertically straight strap-passage between said pairs of supports; spaced aligned horizontal bars integral with the front supports; a button loop integrally depending from said aligned horizontal bars; impositioned open spaces between the supports, of each pair adjacent the loop-ends; and a strap-binding element hinged upon the connecting horizontal bar and adapted to be swung into and across the strap-passage to wedge an inserted strap against the front supports. 5

2. A wire slide loop comprising relatively spaced interfacing companion loop-ends flatly lying in a common horizontal plane with no relative con- 10

nection in said plane; wire ends depending vertically from the loop-ends to provide pairs of rear and front supports; a vertical strap-passage provided between the pairs of supports; a horizontal bar connecting the pair of rear supports; a button loop depending from spaced aligned horizontal bars of the pair of front supports and providing axially associated button-receiving and button-retaining loops having therebetween a constricted throat portion; impositioned open spaces between the supports of each pair adjacent the loop-ends; and a strap-binding element hinged upon the connecting horizontal bar and adapted to be swung into and across the strap-passage to wedge an inserted strap against the front supports. 15

3. A length of wire providing a slide loop having rear and front walls in spaced parallel vertical planes defining a vertically straight strap-passage, the front wall integrally including in its plane a button loop of axially associated loops having therebetween a constricted throat portion, said associated loops providing an unobstructed passage therethrough from the front for the initial insertion of a strap held in a vertical plane, transverse to that of the button loop; a horizontal bar provided by the rear wall as an obstruction to the further direct insertion of the vertically held strap but adapted to guide the strap in its swung entrance to within the strap-passage between said parallel walls; and a latch member hinged to the horizontal bar and adapted to grip and maintain the inserted strap within its vertical passage. 20

GEORGE HENRY ELWELL.
